UNITED STATES PATENT OFFICE.

EUSTACE CREEES AND CHARLES S. COURT, OF PROVIDENCE, RHODE ISLAND,
ASSIGNORS TO THE WAIITE, THRESHER COMPANY, OF SAME PLACE.

DESIGN FOR A HANDLE FOR BUTTON-HOOKS OR SIMILAR ARTICLES.

SPECIFICATION forming part of Design No. 28,557, dated May 10, 1898.

Application filed March 19, 1898. Serial No. 674,543. Term of patent 3½ years.

To all whom it may concern:

Be it known that we, EUSTACE CREEES and CHARLES S. COURT, citizens of the United States, residing at Providence, in the State of Rhode Island, have invented and produced a new and original Design for a Handle for Button-Hooks or Similar Articles, of which the following is a specification, reference being had to the accompanying drawings, forming a part thereof.

Figure 1 represents a side view of a handle showing our new design. Fig. 2 represents a longitudinal section thereof.

As shown in the drawings, the leading or material features of our design consist in the transverse circular beads $a a'$ at the inner end of the handle, the foliated scrolls $b b$, extending from the bead a' to near the outer end of the handle, with the outwardly-curved panels c and d between them, and beyond the inward foliations $e e$ of the scrolls $b b$ is arranged the ribbed ornament f , and within the said foliations $e e$ is arranged the leaf-like ornament g , having the bead h at its base, and at the center of the panel d is arranged the

line of graduated beads i , at the end of which is placed the ribbed ornament j . The outer end of the handle is provided with the spreading ribbed ornamentation k , extending outward from the curved rib l , and between the 30 ornamentation k and the foliated end of the scrolls $b b$ are placed the foliated scrolls $m m$ $m' m'$, and also the foliated scrolls $n n$, which, together with the curved ribs l and l' , form the boundaries of the small panel o , in the 35 central line of which is arranged the line of beads p , and from the curved rib l' as a base is arranged the spreading ribbed ornamentation q .

Having now described our invention, what 40 we claim as new, and desire to secure by Letters Patent, is—

The design for a handle for button-hooks, and similar articles, &c., herein shown and described.

EUSTACE CREEES.
CHARLES S. COURT.
